United States Patent Office.

CHARLES LEAVITT, OF CLEVELAND, OHIO.

Letters Patent No. 64,678, dated May 14, 1867.

FRUIT-DRYER.

The Schedule referred to in these Letters Patent and making part of the same.

TO ALL WHOM IT MAY CONCERN:

Be it known that I, CHARLES LEAVITT, of Cleveland, in the county of Cuyahoga, and State of Ohio, have invented certain new and useful Improvements in Fruit-Dryers, &c.; and I do hereby declare that the following is a full and complete description of the same, reference being had to the accompanying drawings, making part of this specification, in which—

Figure 1 is a perspective view of the dryer.

Figure 2 is a view of the top.

Figure 3 is a transverse vertical section in the direction of the line xx .

Figure 4 is a vertical section in the direction of the line $x'x'$.

Like letters of reference refer to like parts in the different views.

A, fig. 1, represents the case of the dryer, which is constructed of wood, and of a size according to the capacity required. B, fig. 2, is the top, around the sides of which runs a channel or flue, C C'. The sides of the flue C running lengthwise of the case are opened into the interior, whereas the flues crossing the front and rear ends are closed and have no communication with the interior of the case, except at the corners at the ends of the open flues referred to. Also constructed lengthwise across the centre of the top is a flue, D, communicating at each end with the cross-flues C'. The side and end flues, together with the central flue, and their relative connections, are shown in fig. 2, a section of the top being broken away in order that they may be seen, and in which figure C is an open side flue C', the closed end flue, and D the central. These open flues are also shown in fig. 3, in which B is the top of the case. On this case it will be observed that the top does not reach across to the sides, but near to it, leaving a short space between the top and sides open to the interior, and which constitutes the open flue alluded to. On the contrary the top reaches to the ends of the case, as shown in fig. 4, thus making a closed flue, of which the top of the case forms the bottom; so, also, it forms the bottom of the central flue. Access is had to the interior of the dryer through doors E F G, fig. 1. Immediately below the central door is arranged an ordinary furnace, H, of which I I are the outside doors. Connected to this furnace, and reaching back to and through the rear wall of the case, is a heater, J, communicating with the outside pipe or chimney K.

Having thus indicated the general construction and arrangement of the dryer, the practical use of the same is as follows: The fruit or other material to be dried is spread upon open or slatted shelves L, which are then slid into the dryer or case upon rabbeted cleats M, arranged one above another, as shown in fig. 3. The dryer, on being properly filled with shelves and fruit, is then heated up by the furnace and heater above referred to, the smoke passing off through the pipe N to the outside pipe K, while the moisture and other exhalations of the drying fruit pass up through the open flues above described, and are carried by the draught of heated air to the ends of the flues to the upper corners of the dryer, where they intersect the closed or end flues through which they pass to the central flue D, and from thence through the pipe O, to the pipe or chimney K. By this arrangement of the flues it will be evident that the remote upper corners of the dryer will be heated equally with the more central parts, as the excess of heat will be drawn thereto by the natural draught through the end flues which open into the dryer at these points, and which are the only outlets. Thus, the excess of heat and exhalation of the drying fruit escape through common outlets to the outside. Also by thus causing the redundant heat and vapors to pass off around and over the top of the dryer, adds to the heating and drying capacity of the apparatus; hence a less amount of fire is required to accomplish the process of drying.

What I claim as my improvement, and desire to secure by Letters Patent, is—

The herein-described arrangement of the channels or flues C C', and D, in combination with the pipes K and O, case A, for the purpose and in the manner set forth.

CHARLES LEAVITT.
